Guy W. Kirsch, Sturgis, Mich., assignor to Kirsch Company, Sturgis, Mich.

Application September 19, 1938, Serial No. 79,983

Term of patent 14 years

To all whom it may concern:

Be it known that I, Guy W. Kirsch, a citizen of the United States, residing at Sturgis, in the county of St. Joseph and State of Michigan, have invented a new, original, and ornamental Design for a Curtain Rod, of which the following is a specification, reference being had to the accompanying drawing, forming part thereof, in which:

Fig. 1 is a front elevational view of a curtain rod showing my new design; and

Fig. 2 is a side elevational view thereof shown to a somewhat enlarged scale.

The characteristic feature of my design resides in having the rod bend in an even bow from bracket to bracket and held in a plane extending diagonally upwardly and outwardly from the brackets.

I claim:

The ornamental design for a curtain rod, substantially as shown and described.
